(57) **CLAIM**

The ornamental design for a digital voice recorder, as shown and described.

DESCRIPTION

FIG. 1 is a top, front, and right side perspective view of my new design for a digital voice recorder in the open position; FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a front elevation view thereof in the closed position;

FIG. 9 is a right side elevation view thereof in the closed position;

FIG. 10 is a rear elevation view thereof in the closed position; and,

FIG. 11 is a top, front and right side perspective view thereof shown attached to a laptop computer.

The broken line showing of laptop computer on FIG. 11 is for illustrative purposes only and forms no part of the claimed design.
